UNITED STATES PATENT OFFICE.

SWAN NILS TEVANDER, OF MAYWOOD, ILLINOIS, ASSIGNOR TO SWAN METALLIC SEAL & CAP COMPANY, A CORPORATION OF ILLINOIS.

CURLING MACHINE FOR CAPS FOR JARS.

Application filed June 4, 1923. Serial No. 643,209.

This machine is adapted to curl over the edge of a flange or a cap used to cover the top of a jar or receptacle that is to be sealed thereon by a special machine not shown, 5 which changes the shape of the flange or the skirt of the cap from what is shown in these drawings to a form which seals the cap on to the mouth of the jar or receptacle. The function of this machine is simply to curl 10 over the raw edge on the skirt of the cap and to do this in the most expeditious manner and most desirable form from the standpoint of the results arrived at and the mechanism employed which is the object of the 15 invention.

Reference will be had to the accompanying drawings in which Figure 1 is a sectional elevation through a portion of a cap which is prepared ready to be operated upon by 20 the machine. Fig. 2 shows a similar view to that of Fig. 1 but shows the edge of the flange of the cap curled over as the finished product of the machine. To change the edge of the skirt or flange of the cap from that 25 of Fig. 1 to that of Fig. 2 is the function of the machine.

Fig. 3 is a sectional elevation of the machine on line 3—3 of Fig. 14. Fig. 4 is a sectional view through the curling heads 30 or chucks of the machine when the same are in position for receiving the cap to be operated upon. Fig. 5 is a similar view to that of Fig. 4 showing the next progress step of operation of the machine from that 35 of Fig. 4 to Fig. 5. Fig. 6 is a similar view to that of Figs. 4 and 5 showing the parts at the completion of the operation of the curling over of the edge of the flange. Fig. 7 is a similar view to that of Figs. 4, 5, and 40 6 showing the step of discharging a cap from the curling heads or chucks. Fig. 8 is a sectional view through the body of the machine showing the curling heads or chucks in section and their connecting parts. Fig. 45 9 is a vertical sectional elevation on line 9—9 of Fig. 11. Fig. 10 is a plan view showing the caps going from the hopper chute into the curling devices. Fig. 11 is a plan view of the machine. Fig. 12 is a plan 50 detail of a detector device that insures the entry of the caps from the hopper in the right position to be received by the curling chucks. Fig. 13 is a sectional detail of a cam structure, on line 13—13 of Fig. 14. 55 Fig. 14 is a side vertical elevation of the

machine. Fig. 15 is a section on line 15—15 of Fig. 4. Fig. 16 is a section on line 16—16 of Fig. 4.

In the drawing 1 indicates a metal cap lined with a paper lining 2, but instead of metal for the outside portion of the cap I may use any suitable material and likewise I may line with any suitable material besides paper. The lining is secured to the metal by a suitable adhesive which serves to 60 keep the two materials in such close contact that they amount to a single piece in so far as the operation upon the cap is concerned. The cap is first formed as shown in Fig. 1 having its flange beaded as is indicated by 65 4, 5 and 6 and as before stated the purpose of the machine is to curl over the edge 6 in the form indicated by 7 in Fig. 2. Thus the edge of the metal portion is made to overlap the edge of the lining portion which insures against the lining coming loose from the material on the edge of the flange of the cap. Further, these caps are often handled 70 individually by the hand in their further use as caps over jars and vessels of various kinds and were the edge to remain as shown in Fig. 1 it would be a sort of a raw cutting edge from the actions in blanking and forming the caps but with the curled over edge 75 80 85 90 95 100 105 110 a smooth desirable edge is produced.

The caps formed as shown in Fig. 1 are thrown into the hopper 8 of the machine, see Figs. 3 and 11, in a more or less promiscuous shape. An operator stands by the machine and one by one directs the caps down the hopper in a form shown by the dotted lines 9 in Fig. 3 and full lines in Fig. 9.

It is necessary that these caps be rightly positioned in the chute 10 which conducts them from the hopper 8 into the machine and in order that they cannot pass through the machine in any other than the right position I provide a spoked wheel 11 having the spokes 12 and mounted on a pin 13 and adapted to rotate under the influence in the caps 9 passing down the chute 10 as is shown in Figs. 11 and 12. Were the caps to be reversed from the position shown in Fig. 12 the spokes 12 of the wheel 11 would lock the cap from passing further through the chute and by this means the caps are always delivered into the chucks in the right position to be received by them.

The machine is provided with a suitable

frame having the left end post 14 and the right end post 15, see Fig. 14, and these posts sustain a central shaft 16 which acts simply as one of the frame members and also as a mandrel upon which is mounted the operative parts of the machine, some of which are stationary upon the shaft 16 and some of which are mounted to revolve on this shaft.

- 10 As a terminus for the chute 10 to receive the caps 9 there is provided a revolving carrier member 17 which in some respects has the appearance of a toothed wheel or cam and is provided with the pockets 18 and 15 what may be termed the cam surfaces 19 arranged in a manner that as this member revolves it takes out of the chute 10 a single unit of a cap each time one of the pockets 18 revolves past the end of the chute 10, see Fig. 9. This carrier member 17 is secured by the bolts 20 to some studs 21 into a chuck spindle casting 22 which provides the journals 23 in which the chuck spindles 24 revolve. This chuck spindle casting 22 is provided with the hub 25 journaled on to the shaft 16 and is provided with an oil cistern 26, see Fig. 8. Mounted on the chuck spindle casting 22 there is a driving gear 27 which is driven by a pinion 28 on a shaft 29 suitably journaled to the machine frame and driven by a pulley 30 under the influence of a belt 31, connected to the shaft 29 through the medium of a clutch 32 controlled by the operator as desired by the 30 lever 33. For hand movement of the shaft 29 there is provided the hand wheel 34, see Fig. 14. Thus in the normal operation of the machine the chuck spindle casting 22 continuously revolves so long as the power 40 is applied to the shaft 29. Upon the chuck spindles 24 there are keyed the pinions 35 which are engaged and driven by a gear 36 having its hub 37 revolving on the said shaft 16 and upon an extension of this hub 45 37 there is fixed by a key seat and a set screw a driving gear 38 which is driven from the gear 39 on the said shaft 29 through the medium of an idle pinion 40 and the latter being used for the purpose 50 of reversing the direction of the travel of the gear 38 from that of the gear 27. Thus as the gear 27 with its chuck spindle casting 22 revolves, the chuck spindles 24 are made to revolve at a relatively high rate of 55 speed.

The chuck spindles 24 carry chuck blocks 41 suitably fastened on the spindles 24 but here shown as being threaded on, and these blocks 41 carry small grooved curling rollers 60 42 which revolve on pins 43 in the chuck blocks 41.

The spindles 24 are perforated and provided with sliding rods 44 which serve to push the caps from the seat or pocket 18 65 when a cap first arrives from the chute 10

out into the embrace of the holding chucks 45 opposite the chucks 41 and this movement is accomplished by a stationary cam block 46 screwed to a bracket 47 by bolts 48, see Figs. 8 and 14. The cam block 46 works 70 against the rounded end 49 of a bar 50 which carries a spring 51 in an aperture of the bar 50, which spring 51 abuts against the end of the rod 44 and thus connects the rod 44 to the block 50, making the two pieces operate substantially as one with the exception of the adjustment allowed for the spring 51 by a small pin 52 working in a notch 53 of the rod 44. A spring 54 abuts 75 against the end of the block 50 and serves to restore the movement of the parts that are affected by the cam block 46. The movement produced by the spring 54 is limited by a shoulder on the block 50 engaging the cap 55 screwed on to the spindles 24. At the lower side of the machine there is provided the ejecting cam block 56 having the cam surface 57 and supported by the stud 58 and bolt 59 in the frame post 14 of the machine, see Figs. 8 and 13. The purpose of this cam 56 is to eject and discharge entirely the finished cap from the machine.

At the right of the machine and opposite the block or casting 22 and firmly secured thereon to revolve therewith there is the spider casting 61 which provides carrying guideways 62 for rods 63 which are splined in the guideways 62 and are adapted to slide horizontally in the guide 62 but not to revolve therein, and mounted on one end of these rods in fixed position are the holding chucks 45. On the opposite end of each of the rods 63 a cam roller 64 is revolvably mounted on one of the pins 65. These rollers 64 travel in the cam track 66 in a cam block 67 which is firmly fixed on the shaft 16 in a manner to remain stationary substantially as a part of the frame, see Figs. 4, 8, and 14. The shape of this cam track 66 is such that it moves the carrying chucks to and from the chucks 41 in a manner of holding the cap to the work of having the edge curled over by the curling rollers 42. In the revolution of the blocks 22 and 61, the rollers 64 in the cam track 66 move the holding chucks 45 in and out as desired at the several stages of the work and the finished caps are ejected from the holding chucks 45 by the ejector plates 68 supported by pins 69 within the said blocks 45. These plates 68 with their pins 69 simply float in their movement under the influence of the push of the rods 44 in one direction, and the push of some cam plates 70 fastened by screws 71 to the guideways 62. The ends of the pins 69 are made to contact with the plates 70 because of the fact that the plates 70 limit the stroke at which the pins 69 may be drawn to the right when the rods 63 with 80 90 95 100 105 110 115 120 125 130

the chucks 45 are moved to the right to the full limit at the position of the machine where the cap is to be discharged. Thus there is automatically produced the ejection 5 of the cap from the holding chucks 45 when the spider 61 has revolved around to the desired position where the cam track 66 withdraws the rods 63 to the full limit to the right which is the position for discharging 10 the finished cap from the machine and is the position whereat the cam block 56 forcibly pushes the rods 44 to eject the caps from the curling chuck 41.

A cam ring 72 having the cam tracks 73, 15 see Figs. 10, 11, and 14, is fastened by screws 74 to the guideways 62 and thus the cam ring 72 revolves with the spider 61 substantially as a part thereof. The purpose of this cam ring 72 and its cam tracks 73 20 is to actuate at the proper moment the pin 75 to hold or dam off the caps 9 from flowing out of the end of the chute 10 during the travel from chuck to chuck as the chucks revolve past the mouth of the chute 10. 25 This pin 75 is held in a keeper plate 76 secured to the chute 10 by the screws 77, see Fig. 9, and a spring 78 working against a collar 79 keeps the pin 75 always in position of contact with the last cap 9 in the 30 chute, and it is the function of the cam tracks 73 of the ring 72 to momentarily release the contact of this pin 75 with the caps when it is desired that one should roll by gravity into the pocket 18 of the carrier 35 plate 17. The connection between the pin 75 and the cam track 73 is brought about by a plate 80 through which the head of the pin 75 passes and the plate 80 is hinged by the screw 81 to the frame member 82 of the 40 machine. Thus as the chucks are revolved one by one the caps are allowed to roll out of the chute 10 at the proper interval to register in the carrying pockets 18.

The arrangement of the machine as described permits a continuous revolution of 45 the chucks past the chute 10 and at the proper interval a cap is taken out of the chute and by the action of the cam tracks before described the cap is first pushed by 50 the rods 44 from the position shown in Fig. 4 over into the position in Fig. 5 which results in the cap being held firmly in the carrying chucks 45 there being a snug fit of the cap into the flange 83 of the chuck 45. From the position of Fig. 5 the cam track 66 forces the rods 63 over to the position of Fig. 6 bringing the edge 6 of the flange of the cap into the curling groove of the rollers 42 which rollers are carried 60 around rapidly by the rapid revolution of the spindles 24 through the medium of the gearing previously described. There being three of these rollers 42 in each chuck 41 working as a balance upon the flange of the cap they rapidly curl over the edge of the 65

flange of the cap to the position shown by 7 in Fig. 2 and by the time any single set of chucks 41 and 45 have traveled from the mouth of the chute 10 around to the lower side of the machine the curling of the edge 70 of the cap has been completed and the cap discharged to the position of Fig. 7, and the caps immediately drop out of the machine as soon as the rod 44 is drawn back again by the spring 54 when permitted to do so 75 by the end 49 of the bar 50 immediately upon the clearance from the cam block 56. Thus the operation of the machine is substantially as rapid as the operator may 80 properly supply the caps in the right position in the chute 10.

What I claim is:—

1. In a device of the class described, a chuteway adapted to deliver caps in succession, a constantly moving carrier member, 85 a series of holding chucks mounted on one side of the said carrier member and a series of curling chucks mounted on the other side of the said carrier member, the said holding chucks being stationary as relates to rotating movement but adapted to move longitudinally at approximately right angles to the said carrier member, and said curling chucks adapted to be revolved about the axis of the cap and provided with grooved curling 90 rollers to engage the flange on the cap and curl the same back upon itself, ejector mechanism for moving both sets of chucks in alignment with each other, stationary cam tracks and mechanism connected therewith 95 for forcing the caps into the embrace of the holding chucks and also for discharging them from the curling chucks; in combination with suitable gearing and source of power for revolving the said chucks and carrier member past the said chuteway and for simultaneously revolving the said curling 100 chucks.

2. In a device of the class described, a delivery chute adapted to deliver caps successively to curling chucks, a curling chuck adapted to be revolved about its axis and also revolved past the said delivery chute for the caps, a holding chuck oppositely faced from the said curling chuck and in 110 alignment therewith and adapted to be revolved bodily but not circumferentially in association with the said curling chuck and provided with an ejector mechanism carried within the body of the holding chuck and in 115 alignment therewith and adapted to be revolved in unison in relation to the said delivery chute and mechanism for automatically moving the holding chuck to and from the curling 120 chuck.

3. In a device of the class described, means for delivering properly positioned cap blanks, a plurality of curling chucks each provided with a plurality of curling rollers, 125 an oppositely faced holding chuck for each 130

- curling chuck, means for revolving said curling and holding chucks about a common axis, means for revolving each curling chuck about its axis, cap ejecting means for each curling chuck and means for reciprocating each holding chuck into and out of engagement with a cap on a co-acting curling chuck.
4. In a device of the class described, the combination with a plurality of curling chucks each provided with a plurality of curling rollers mounted to revolve freely on axes perpendicular to the axis of the curling chuck, means for rotating each curling chuck about its axis, means for supplying properly positioned caps to said curling chucks, a plurality of cap holding chucks adapted to hold a cap while operated upon by a co-acting curling chuck, means for rotating said curling and holding chucks about a common axis, and means for releasing the curled caps.
5. In a device of the class described, the combination with a revolving spider having a plurality of longitudinal bearings, a plurality of curling chucks, each having a plurality of curling rollers, and mounted in said revolving spider, a holding chuck for each of said curling chucks, means for revolving said spider, means for revolving in a reverse direction said curling chucks in said bearings in said spider, means for reciprocating said holding chucks in succession, reciprocating means for releasing a finished cap from said chucks.
6. In a device of the class described, curling mechanism for curling the flange of a cap upon itself, a chuteway for delivering caps to the said curling mechanism, mechanism for insuring the delivery of the caps in the right position from the chute, mechanism for intermittently shutting off the delivery of the caps to the said curling mechanism, two series of chucks one composed of members for holding caps and the other series for operating on the caps, means for moving the two series in relation to each other in a manner to embrace and release the cap, and means for moving both series past the delivery end of said chute and receiving therefrom in succession caps to be operated upon, together with means for revolving one series of the said series of chucks, and means carried within one of the series for curling over the edge of the caps.
7. In a device of the class described, a frame having a central supporting fixed shaft fixed in the said frame and adapted to furnish an axis for supporting revolving and fixed members, revolving and fixed members mounted upon said fixed supporting shaft, some of the said fixed members being provided with cam tracks, a series of rods carried by the revolving members and mounted to move in parallel relationship with the axis of said fixed shaft and adapted to be engaged and moved by the said cam tracks, a series of spindles carrying chucks, the said rods mounted within the said spindles, a series of chucks mounted on the said spindles, said chucks provided with curling rollers adapted to curl over the flange of a cap upon itself, gearing mounted on the said fixed shaft and connected to be driven and carry with it the said revolving members.
8. In a device of the class described, a delivery chute for caps, a revolving spindle, a rotating and moving chuck mounted upon said revolving spindle adapted to operate and curl over a flange of a cap upon itself, means for carrying the said chuck to and from said delivery chute for the caps, means contained within the said spindle of the said chuck for moving a cap longitudinally and parallel with the axis of the said spindle, stationary cam tracks past which the said spindle of the said chuck is moved, said cam tracks adapted to actuate the said means within the said spindle for moving the said cap.

Signed at Chicago, in the county of Cook, and State of Illinois, this 9th day of April, 1923.

SWAN NILS TEVANDER.
